UNITED STATES PATENT OFFICE.

JOSEPH C. FOWLER, OF HOUSTON, TEXAS, ASSIGNOR OF ONE-HALF TO
SINCLAIR TALIAFERRO, OF SAME PLACE.

CAR-COUPING.

SPECIFICATION forming part of Letters Patent No. 252,292, dated January 10, 1882.

Application filed November 25, 1881. (No model.)

To all whom it may concern:

Be it known that I, JOSEPH C. FOWLER, a citizen of the United States, residing at Houston, in the county of Harris and State of Texas, have invented new and useful Improvements 5 in Car-Couplings, of which the following is a specification.

The object of this invention is to provide a car-coupling, which in the event of a car running off the track and tipping over, will automatically uncouple; also, to provide a coupling-pin which will be locked down by reason of the strain thereon when the cars are in motion; also, to provide certain improvements in 15 the details of construction of the coupling, as hereinafter set forth, and illustrated in the drawings, in which—

Figure 1 is an end view of the draw-head and coupling-pin. Fig. 2 is a longitudinal section taken on a vertical plane to one side of the coupling-pin. Fig. 3 is a like section, the parts being viewed from an opposite direction. Fig. 4 shows a modified form of coupling-pin.

A indicates the draw-head, and B the coupling-pin, which is adapted and arranged to engage with the usual coupling-link. The draw-head has slots formed through its top and bottom portions, and the vertically-movable coupling pin is arranged to work through the said slots. The draw-head is also provided upon its top side with a casing, a, through which the upper portion of the coupling-pin passes, whereby the pin is steadied and guided in its movements. The coupling-pin is provided 25 with a horizontal cross-pin, C, the ends of which are arranged to work within the slots D, that are formed in the inner vertical sides of the draw-head. The coupling-pin has a shoulder or offset, E, formed in its rear edge, 30 which divides said edge into the two straight portions e e'. Along the upper portion of its front edge the coupling-pin is made straight, and at the lower portion thereof it is curved so as to form a point at the lower end of the 35 pin. This said coupling-pin is normally held down, so that its cross-pin will be at the lower ends of the slots, by means of a spring, F, secured upon the draw-head and arranged to bear upon a stud or projection on the rear edge 40 of the coupling-pin.

The ordinary link, G, is employed in connection with the coupling-pin, and it is engaged thereby as follows: The link strikes and presses against the front curved edge of the coupling-pin, thereby forcing the pin C out of 55 the notches d, and raising the coupling-pin against the spring-pressure until the coupling-link passes under the point of the pin, when the latter will be promptly thrown or forced downward by the action of the spring F. It 60 will be seen that when the link is thus engaged by the coupling-pin the horizontal cross-pin will rest upon the link, and thereby hold the link in a horizontal position and prevent it from sagging on either side. By this means 65 the link will be maintained in proper position for engaging the coupling-pin of another car. When the link is held by the pin, as just related, the ends of the horizontal cross-pin will be at the lower ends of the slots D, and when 70 the train is in motion the lateral strain of the link upon the coupling-pin will draw the ends of the horizontal cross-pin into notches d, formed at the lower ends of the inclined slots, thus locking down the coupling-pin and preventing its being accidentally raised. But, should 75 a car run off the track and tip over, the link will turn about its axis—that is to say, a central line taken longitudinally through the greatest length of the link—whereby one side of the 80 link will bear upon the inner surface of the bottom of the wall of the draw-head, while the opposite side of the link will rise, and, acting against the horizontal cross-pin, raise the coupling-pin sufficiently to admit of the link slipping 85 from under the same. This then will uncouple the cars, and thereby tend to avoid any accident to the cars in rear of the one which has jumped the track. When the coupling-pin is raised to the farthest extent the shoulder or 90 offset on the rear edge of the coupling-pin will abut against the top wall of the recess on the draw-head, thus relieving the cross-pin of a portion of the shock and strain.

Any suitable lever or other desirable device 95 or devices can be employed for raising the coupling-pin when it becomes necessary to uncouple.

In applying the coupling-pin it will be passed up through the slot in the bottom of the draw- 100

head, and the cross-pin will be passed through a hole in the side of the draw-head and driven through the coupling-pin.

In the modification shown in Fig. 4 the coupling-pin is formed with a curved front edge, against which the link strikes. The body of this pin will be arranged horizontally within a slot formed through the upper part of the draw-head, the rear end of the coupling-pin 10 or latch being slotted to receive a pivot that will be secured at the sides of the draw-head. This form of pin or latch will have a notch, *i*, which will receive the link when the cars are coupled, and will have the horizontal cross-bar, as in the first-described coupling-pin. It will be evident that the operation of the latch will be substantially the same as the vertically-sliding coupling-pin, and that a spring can be applied to hold the same down.

20 I am aware that a coupling-block has been formed at its lower end with a beveled projection to enter a coupling-link, the end of the coupling-block on opposite sides of the beveled projection serving to rest on the link to 25 hold it in a level position. Such construction is not my invention, as I provide the coupling-pin with a transverse pin the ends of which rest in vertical grooves in the side walls of the draw-head, which is the essential feature of 30 my invention.

Having thus described my invention, what I claim, and desire to secure by Letters Patent, is—

1. In a car-coupling, the vertically-movable 35 coupling-pin, provided with a horizontal cross-bar adapted to rest upon the link when the latter is engaged by the coupling-pin, substantially as described.

2. The combination, with the draw-head having grooves in its inner vertical walls, of the 40 coupling-pin provided with a horizontal cross-bar having its ends received into the said grooves, substantially as and for the purpose described.

3. The combination, with the draw-head having grooves in its inner side walls, with notches at the lower ends of said grooves, of the coupling-pin provided with a horizontal cross-bar having its ends received in the said grooves, whereby lateral strain on the coupling-pin in 50 a forward direction when the pin is down will draw the ends of the cross-bar into said notches and thereby lock down the coupling-pin, substantially as described.

4. The combination, with the draw-head having grooves in its inner side walls, of the coupling-pin provided with a cross-bar having its ends received into said grooves, and the spring arranged to depress the coupling-pin, substantially as described.

5. The combination, with the draw-head, of the coupling-pin provided with a cross-bar having its ends received in grooves in the draw-head, said coupling-pin being formed with the shoulder or offset *E* on its rear edge, whereby 65 the shock and strain upon the cross-bar when the coupling-pin is raised will be partly relieved, substantially as described.

In testimony whereof I have hereunto set my hand in the presence of two subscribing 70 witnesses.

JOSEPH C. FOWLER.
